UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR.

Original application filed December 6, 1920, Serial No. 428,438. Divided and this application filed December 4, 1924, Serial No. 752,794.

This invention relates to electrical insulators, and especially to insulators for high voltages, and has for its object improved distribution of electrostatic flux and the provision of insulators which shall be of improved construction and operation.

The invention is exemplified in the combination and arrangement of parts shown in the accompanying drawings and described in the following specification, and it is more particularly pointed out in the appended claims.

This is a division of application, Serial No. 428,438, filed December 6, 1920, Patent No. 1,521,743, dated January 6, 1925.

In the drawing, the figure is a vertical sectional view of an insulator embodying one form of the present invention.

In high tension insulators where two conductors of different potentials are separated from one another by an insulating member, it is well known that an electrostatic field is present in which the lines of force extend through the insulator and the surrounding medium from one of the conductors to the other. Other conditions being equal these lines of force are most closely concentrated at the portions of the insulated conductors which are nearest to one another. The lines of force also concentrate at restricted projections or points formed upon the conductors.

When insulators or dielectrics are worked at high pressures or potentials the resulting high electrostatic density may set up a stress of such magnitude that it will damage the dielectric. This stress may be set up around a conductor imbedded in a solid dielectric or around a conducting surface which operates in a medium, such as air, oil, wax, or other medium. When the conducting surface operates in air, corona or brush discharge may occur at a fairly low voltage, particularly where the conductor has a sharp edge or point. If corona or brush discharge occurs at normal frequency, say 60 cycles, and an electrical stress at high frequency is impressed on the electrodes, the current will be increased in the streamer or brush discharge. Since the resistance of the streamer drops off very rapidly with an increase in the current it is seen that where the frequency is high the

current may be very materially increased. This increase in current lowers the resistance in the streamer permitting the streamer to flow out further from the electrode. This increase in distance increases the capacitance of the streamer and permits more current to flow. The increased current in turn still further lowers the resistance in the streamer so that it extends still further. Where a persistent wave at high frequency is applied, such as in wireless work, a comparatively small voltage will cause the streamer to build out several feet once it is started. This streamer may arc to ground or absorb considerable energy or damage any insulator which may be near the surface which discharges.

In wireless work where a high frequency generator is used, or the equivalent, the point of brush discharge from a conducting surface limits the voltage which may be used. If this discharging surface is covered by a dielectric having greater strength than the air, it will be possible to operate at a higher voltage or stress, since a streamer, which will grow to serious proportions, is prevented. It will be seen that where this is the condition and a strong dielectric is used to cover the surface which has greatest tendency to discharge, a higher operating voltage may be used.

If a conducting surface has a tendency to discharge, the bringing of another surface charged with the same potential near will screen the first surface or reduce part of the concentration of stress. The added surfaces forms a parallel path or circuit for the electrostatic flux and hence reduces the amount of flux emanating from the original surface. Where the screening surface is insulated it may be placed in a stronger field without danger of discharging. This will permit it to be so placed that it will greatly reduce the concentration of flux from some uninsulated surface. This insulated screen or shield may be effectively used to set up a better electrical gradient in the insulator or surrounding medium and permits operation at a higher potential without setting up streamers on the metal parts of an insulator or a charged surface with which it is used.

The above is applicable to high tension

lines for there is often a strong tendency for the line to arc to ground at the insulator. This tendency to arc is greatly aggravated by surges on the system produced by 5 resonant arcing to ground, switching surge, poor wave form or electrical discharge, such as lightning. Any condition such as those named above that produces a high voltage wave or series of waves in the line will, of course, increase the tendency to arcing at 10 the time of increased voltage. The starting up or slowing down of a generator excited and connected to a parallel circuit may set up a resonant condition and cause arcing 15 of insulators from streamers which develop in the manner described.

In the drawing, the numeral 10 designates an insulator which may be a simple bar, or which may be of any cross-sectional shape, 20 which working conditions require. To one end of the insulator 10 is secured a cap 11 provided with a supporting ring 12 and connected to the end of the insulator by cement 13. The cap 11 is provided with a number 25 of arms 14 extending toward the opposite end of the insulator and arranged to carry a shield of insulating material 15. The shield 15 is turned backwardly at 16 providing a rearwardly extending fold 17, and 30 the surface of the insulator within the backwardly turned portion is plated with a coating of conducting material, as indicated at 18. The plating 18 extends backwardly along the shield 15 and is electrically connected with the arms 14 and the cap 11 by a winding of metal wire 19 interposed between the shield 15 and the arms 14 for securing the shield in place within the arms. 35 It will thus be seen that the plating 18 is electrically connected with the conductor secured to the end of the insulator, and that the foremost portion of the plating 18 being the nearest to the opposite conductor will constitute the source from which the greatest number of electrostatic lines of 40 force will emanate toward the conductor at the opposite end of the insulator. It will be apparent that these lines of force must pass through the dielectric material of which the shield 15 is composed, and since this material is of greater dielectric strength than the surrounding medium, the shield 15 will offer an effective resistance to any tendency 45 to flashover along the lines of force of the concentrated electrostatic field. The plating 18 also provides an extended smoothly curved surface so that there are no points to cause a concentration of the electrostatic flux. It is sometimes desirable to provide a 50 filling of conducting material between the front edge of the end cap 11 and insulator 10, as shown at 20. This will protect the cement 13 from any leakage currents between the cap and the surface of the insulator.

The end of the insulator is provided with

a longitudinally extending opening 21 into which a pin 22 connected with the cap 11 projects. The pin 22 may be secured to the interior of the opening 21 by cement 23 to form a supplemental interior connection between the cap and the insulator. The end of the pin 22 constitutes a radiating point for the electrostatic flux, which like the plating 18 is surrounded by an insulating medium of greater dielectric strength than that of the atmosphere. The inner surface of the opening 21 may be plated with a metallic coating 24 similar to the coating 18, and this coating should extend over the rounded surface at the inner end of the opening where it forms electrical contact with the end of the pin 22. The coating may also extend to the end of the insulator so that it forms contact with the end of the cap 11.

The opposite end of the insulator may be 85 provided with a duplicate of the attachment described, or it may be equipped, as shown, with a simple cap 26 and an internal pin 27, similar to the pin 22.

It is not essential to beneficial operation 90 of the invention that the coating 18 be in electrical contact with the arms 14 since streamers will bridge the space between the arms 14 and coating 18 even when there is 95 considerable gap. If the coating 18 be omitted the line of force emanating from the members 14 are intercepted by the member 15 and, in some cases, discharge streamers from these arms will form, in effect, a conductor 100 coating for the cavity within the member 15.

I claim:—

1. An insulator comprising an elongated bar of dielectric material, fittings secured to said bar at opposite ends thereof, and an electrostatic screen supported upon one of said fittings, said screen comprising a cup-shaped plate of dielectric material surrounding said elongated bar, said plate being bent backwardly at its edges to overlie the extremities of the fitting to which said plate is secured. 105

2. An insulator comprising an elongated bar of dielectric material, fittings secured to the opposite ends of said bar, one of said fittings having fingers formed thereon extending in the general direction of the length of said bar, and an electrostatic screen comprising a plate of dielectric material supported by said fingers and surrounding said bar, the edge of said plate extending away from said fingers being bent backwardly to intercept lines of force emanating from said fingers. 115

3. An insulator comprising an elongated bar of dielectric material, a fitting secured to one end of said bar, and a dielectric screen carried by said fitting and surrounding said bar, said screen comprising a plate of dielectric material having the edges thereof disposed away from said fitting bent out. 125

wardly and backwardly to form a recess separated from said bar by said plate, and a coating of conducting material on the inner face of said recess, said fitting having supporting means thereon for said screen disposed outside of the inner portion of said plate.

4. An insulator comprising an elongated dielectric bar, a cap secured to one end of said bar, a conductor connected with said cap and extending into an internal opening in the end of said bar, an external flux screen supported by said cap and surrounding said bar, said screen comprising a plate of dielectric material having the edge thereof disposed away from said cap bent outwardly and backwardly, and a coating of conducting material on the edge of said plate adjacent said cap, said coating being electrically connected with said cap and supporting means on said cap extending outside of the inner portion of said plate.

15 5. An insulator comprising an elongated member of dielectric material, a cap secured to one end of said member and having attaching means formed thereon and spaced from said dielectric member, a plate of dielectric material connected with said attaching means and interposed between said attaching means and said dielectric member, said plate extending beyond said attaching means in the direction of the length of said dielectric member, the extremity of said plate being bent outwardly and backwardly towards said attaching means, and a covering of conducting material electrically connected with said attaching means and disposed on the surface of said plate included in the recess formed by the bend therein.

20 6. An insulator comprising a bar of dielectric material, caps secured to the opposite ends of said bar, internal electrostatic flux distributing members secured to said caps and disposed within openings in the opposite ends of said bar, and an external flux screen secured to one of said caps and surrounding said bar, said external screen comprising a plate of dielectric material having the edge thereof away from its supporting 50 cap bent outwardly and backwardly and

having a coating of conducting material disposed on the surface of said plate included in the recess formed by said bend, said cap having supporting means thereon disposed outside of the inner portion of said plate. 65

7. The combination with an insulator having a fitting at one end thereof, of a dielectric screen comprising a ring of dielectric material, U-shaped in cross section, surrounding said insulator and having the opening of the U directed towards said fitting, and conducting means extending from said fitting to the outside of the inner leg of the U formed by said screen. 70

8. The combination with an insulator having a fitting secured to one end thereof, of a flux screen comprising a dielectric ring, U-shaped in cross section, surrounding said insulator and providing spaced petticoats having their edges directed toward said fitting, and supports for said screen extending from said fitting to the outer surface of the inner petticoat. 75

9. The combination with an insulator having a fitting secured to one end thereof, of a flux screen comprising a dielectric ring, U-shaped in cross section, surrounding said insulator, and providing spaced petticoats having their edges directed towards said fitting, and a support for said screen extending from said fitting to the outer surface of the inner petticoat, said inner petticoat being longer than the outer petticoat. 80

10. The combination with an insulator having a fitting secured to one end thereof, of a flux screen comprising a dielectric ring, U-shaped in cross section, surrounding said insulator and providing spaced petticoats having their edges directed toward said fitting, a support for said screen extending from said dielectric member to the outer surface of the inner petticoat, and a coating of conducting material disposed on the surface of said screen within the space between said petticoats. 85 90 95

In testimony whereof I have signed my name to this specification on this 29th day of Nov. A. D. 1924.

ARTHUR O. AUSTIN.
